UNITED STATES PATENT OFFICE

WALTER F. HEER, OF BEXLEY, OHIO

TEMPORARY BOOKBINDER

Application filed April 16, 1930. Serial No. 444,780.

This invention relates to means for the binding of various legal forms, commercial form, business forms, or any other sort of blanks that may be used in any office, whether public or private.

The invention is particularly advantageous in the binding of blank forms when padded as it admits of any desired blank being easily and conveniently removed from the binder 10 without disturbing the rest.

The invention contemplates a head to be attached to the back of a cover, plates removably connected to the head by projections thereon engaging slots of the head, and 15 a latch associated with the head to retain the book plates in place when in engagement therewith.

While the drawings illustrate a preferred embodiment of the invention, it is to be understood that in adapting the means to meet specific needs and requirements, the design may be varied and changes in the minor details of construction may be resorted to within the scope of the invention as claimed, 25 without departing from the spirit thereof.

For a full understanding of the invention and the merits thereof, reference is to be had to the following description and the drawings hereto attached, in which:

30 Figure 1 is a top plan view of the invention applied, the cover being open and parts broken away.

Figure 2 is a detail sectional view on the line 2—2 of Figure 1.

35 Figure 3 is a perspective view of the binder, the latch and the plate adapted to receive the hook or other article being detached.

Figure 4 is a front view of the device partly in section and with parts of the front broken away.

Figure 5 is a horizontal section on the line 5—5 of Figure 4.

Figure 6 is a sectional detail view on the line 6—6 of Figure 4.

45 The binder comprises a head or holder 1 and a plurality of plates 2, one being provided for each article to be attached to the head or holder. The head 1 is elongated and hollow and comprises a top 3, a back 4, a front 5, and ends 6. The head is adapted to

be attached to the back 7 of covers 8 and is provided at intervals in its length with slots 9 which extend across the front 5 and top 3. The receiving ends 10 of the slots 9 are widened and are formed wholly in the top 3. A 55 latch 11 is slideable in the head 1 and consists of a plate having a lateral flange 12 at its top edge, said flange being disposed against the under side of the top 3 with the plate 11 placed against the back wall 4 of the head 60 1. A finger piece 13 is rigidly attached to the latch and its shank passes through a slot 14 formed in the top 3 of the head. In this manner, the latch 11 is held in place and limited in its sliding movement. The flange 65 12 has a portion cut away, as indicated at 12a, to register with the left hand slot 9 when the latch is moved to the left so that a pad 15, or other article, may be placed in position or removed from the head 1 of the binder. 70

The numeral 15 designates a pad, or tablet of forms, sheets, or other article to be bound and is provided with a plate 2 adjacent an end, said plate being attached to the back of the pad or tablet 15 by means of an adhesive 75 strip or in any determinate manner. Projections 16 are located at intervals in the length of the plate 2 and correspond in position with the slots 9 of the head 1. Each of the projections 16 comprises a head and neck, 80 the head being readily passable through the enlarged receiving end of the slot 9, and the neck being of a width to be retained within the slot 9. As indicated, the projections 16 are of T-form and the receiving slots 9 are 85 of corresponding outline. When the latch 11 is moved to clear the slots 9, the plates 2 may be readily applied to or removed from the head 1 and when applied to the head are prevented from casual disengagement by the 90 latch which is moved to occupy a position to close the receiving ends 10 of the slots 9.

The articles to be bound may be provided with projections 16 in any determinate way and these projections are of such formation 95 and position as to readily coact with the slots 9 of the head 1 and are retained within the head by means of the latch in the manner stated. In the preferred construction, the several parts comprising the binder are 100

formed from sheet metal, thereby providing an article which is light and adapted to be manufactured at a small cost.

What is claimed is:

- 5 1. A temporary binder comprising a head embodying a back and front wall and a connecting top wall and having a slot extending across the front wall and terminating in a wider opening in said top wall, an article to
10 be attached to the head provided with a projection passable into and out from said slot, and a latch mounted upon the head and comprising a plate having a lateral flange along its top edge to extend across and close the receiving end of the slot formed in the top of the head, and a finger piece connected with the latch and operable from a point without the head.
2. A temporary binder comprising a hollow head including a top, and front and back walls, said front having slots therein extending across the top and widened at their receiving ends, an article-supporting plate provided with projections adapted to engage the
25 said slots of the head, and a latch mounted within the head and comprising a plate and a lateral flange, the latter being disposed against the inner side of the top to close the receiving ends of the slots formed therein,
30 and a finger piece connected with the latch and serving as operating and retaining means therefor.
3. A temporary binder comprising a hollow head having slots extending across the
35 front and top thereof and widened at their receiving ends, a plate provided with projections to engage the slots of the hollow head, a latch within the head embodying a plate and lateral flange, the latter being disposed against the under side of the top and adapted to close the receiving ends of the slots, and a finger piece connected to the latch and operable in a slot formed in the top of the head to retain the latch in place and limit
40 the sliding movement thereof.
4. A temporary binder including an elongated hollow head having slots extending across the front and top thereof and widened at their receiving ends, article-supporting
50 plates provided with projections passable through said slots, each of the projections including a head and a neck, a latch slideable within the head and comprising a plate and lateral flange, the latter being disposed
55 against the under side of the top and adapted to close the receiving ends of the slots formed therein, and a finger piece connected with the latch and operable in a slot formed in the top of the head.
- 60 In testimony whereof I affix my signature.
WALTER F. HEER. [L. S.]
